STARTING AND OPERATING CIRCUITS FOR GASEOUS ELECTRIC DISCHARGE DE- VICES

Hans Ewest, Berlin-Lichterfelde-Ost, and Martin Reger, Berlin-Charlottenburg, Germany, as signors to General Electric Company, a corporation of New York

**Application February 20, 1936, Serial No. 64,962
In Germany February 28, 1935**

1 Claim. (Cl. 176—124)

The present invention relates to starting and operating circuits for gaseous electric discharge devices and more particularly the invention relates to such circuits comprising a capacitance and an auto-inductance connected in series with the device across the terminals of an alternating current source which capacitance and inductance are so dimensioned with respect to each other that a resonance voltage is generated thereby.

5 The resonance voltage effects a quick ionization of the discharge path to facilitate the starting of the discharge and is particularly efficacious when auxiliary, starting electrodes are mounted in the device.

10

15 We have observed that when the gaseous electric discharge device in a circuit of the above type comprises a main discharge supporting electrode having a body of highly electron emissive material associated therewith this material is deleteriously affected by the sudden current surges at said main electrode resulting from the discharge of the capacitance. The useful life of the main electrode and the discharge device is thus reduced.

25 The object of the present invention is to provide a starting and operating circuit of the resonant type for a gaseous electric discharge device in which detrimental current surges at the main discharge supporting electrodes are avoided
30 to increase the useful life of the device. Still further objects and advantages attaching to the circuit and to its use and operation will be apparent to those skilled in the art from the following particular description.

35 The invention attains its objects by connecting in parallel with the gaseous electric discharge device two choke coils and a capacitance connected in series with each other with the capacitance connected between the choke coils. The gaseous electric discharge device is provided with two auxiliary electrodes each mounted adjacent a main discharge supporting electrode and connected into the resonance circuit between a choke coil and the capacitance. The above described circuit avoids detrimental current surges at the main electrodes and each of the choke coils connected in series generate high voltages which are impressed on the auxiliary electrodes to facilitate the starting of the main discharge in the gaseous electric discharge device.

In the drawing accompanying and forming part of this specification an embodiment of the invention is shown schematically.

auxiliary discharges and the main discharge between said electrodes 2 and 3 is quickly started. 55

5
10
15
20
Container 1 having main discharge supporting electrodes 2 and 3 sealed therein at each end thereof. Said electrodes 2 and 3 comprise an electron emitting material, such as an alkaline earth oxide, and are heated to an electron emitting, discharge supporting temperature during the operation of the device by the current flow therethrough and the voltage drop thereat. Auxiliary, starting electrodes 15 and 16 are sealed into said container 1 adjacent said main electrodes 2 and 3, respectively. Said container 1 has a gaseous atmosphere therein comprising a gas, a metal vapor, or a mixture of gas and metal vapor, such as a mixture of argon and mercury vapor. The pressure of the gaseous atmosphere is in the range of a few mm. to hundreds of mm., when desired. The main electrodes 2 and 3 are connected to the terminals 8 and 5, respectively, of an alternating current source by the current leads 6 and 4, respectively. A ballast resistance 7 is connected into the current lead 6.

The electrodes 2 and 3 are bridged by the current lead 9 which has two choke coils 11 and 12 connected therein and a condenser 10 connected in series with and between said choke coils 11 and 12. The auxiliary electrodes 15 and 16 are connected to the lead 9 between the choke coil 11 and the condenser 10 and between the choke coil 12 and the condenser 10, respectively, by the leads 13 and 14, respectively. The condenser 10 and the choke coils 11 and 12 are of such size with respect to each other that at the frequency of the alternating current source resonance voltages occur at said choke coils 11 and 12 and at said condenser 10. 35

When potential is applied to the above described circuit the resonance voltage at the choke coil 11 is impressed on the auxiliary electrode 15 and initiates a gaseous electric discharge between said auxiliary electrode 15 and the main electrode 40 2. Similarly the resonance voltage at the choke coil 12 is applied to the auxiliary electrode 16 and initiates a gaseous electric discharge between the auxiliary electrode 16 and main electrode 3. Simultaneously the resonance voltage at the condenser 10 is impressed on the two auxiliary electrodes 15 and 16 to initiate a gaseous electric discharge between said auxiliary electrodes 15 and 16. These three gaseous electric discharges together extend along the entire length of the main discharge path between said main electrodes 2 and 3. The gas throughout the length of the main discharge path is quickly ionized by the auxiliary discharges and the main discharge between said electrodes 2 and 3 is quickly started. 50 55

The quick starting of the main discharge is facilitated by the above described circuit not only when potential is first applied to the circuit but also on each half cycle of the alternating current 5 source.

While we have shown and described and have pointed out in the annexed claims certain novel features of the invention, it will be understood that various omissions, substitutions and changes 10 in the forms and details of the circuit illustrated and in its use and operation may be made by those skilled in the art without departing from the broad spirit and scope of the invention, for example, a choke coil or a condenser is used in place 15 of the ohmic resistance 7, when desired, and in this case the choke coils 11 and 12 or the condenser 10 are reduced in size when the suggested substitution results in an increased impedance in the series resistance. When desired, a plurality of 20 condensers are connected in series between the choke coils 11 and 12.

What we claim as new and desire to secure

by Letters Patent of the United States, is:—

A starting and operating circuit for a gaseous electric discharge device comprising in combination, an alternating current source, a gaseous electric discharge device connected across the 5 terminals of said current source, and having an auxiliary electrode mounted adjacent each of the main electrodes sealed therein, an impedance connected in series with said discharge device and a resonance circuit connected in parallel 10 with said gaseous electric discharge device, said resonance circuit comprising two inductances and a capacitance connected in series, said capacitance being connected between said inductances, the auxiliary electrodes of said device being connected into said resonance circuit on opposite sides of said capacitance to facilitate the starting 15 of the main discharge in said gaseous electric discharge device.
